FURNITURE SUPPORT

John Carlton Ward, Jr., Rome, N. Y., assignor,
by mesne assignments, to Burton-Dixie Cor-
poration, a corporation of Delaware

Application September 6, 1934, Serial No. 742,928

3 Claims. (Cl. 16—33)

This invention relates to furniture and more particularly to articles of furniture the use of which requires the frequent moving thereof, but which must be stationary when supporting a person's weight. For example, the movable member or section of a conventional type of studio bed is usually arranged to form a couch or divan during the day, and when so employed to be positioned over and conceal a second member or stationary section which is generally in the form of a low cot. When either or both members are to be used as beds the movable member is rolled away from its position over the cot, whereupon both are available for sleeping purposes. For convenience it is essential that the movable member be easily and readily movable, yet it is apparent that when in use either as a couch or as a bed it must be stationary.

An object of this invention is to provide an improved supporting mechanism or foot for articles of furniture of the type set forth, so constructed and arranged as to automatically prevent movement when the furniture is under a load, while permitting easy rolling at a mere touch when unloaded.

A further object is to provide a supporting foot for articles of furniture which can be easily and cheaply manufactured from sheet metal by conventional tools and dies.

These and other objects which will be apparent to those skilled in this particular art are accomplished by the invention illustrated in the accompanying drawing in which,

Fig. 1 is a top plan view of one front foot and one rear foot constructed in accordance with one embodiment of this invention shown in connection with a piece of furniture such as the movable member of a studio bed, the frame of which is indicated generally by broken lines.

Fig. 2 is a view in elevation of the device shown in Fig. 1, the view being a section of the associated article of furniture on the line 2—2 of Fig. 1, the article being indicated generally by broken lines.

Fig. 3 is a plan view partly in section of an improved form of yieldable castor mechanism forming a part of the present invention.

Fig. 4 is a side elevation of the mechanism shown in Fig. 3, and

Fig. 5 is a sectional view on the line 5—5 of Fig. 4.

The present invention comprises a supporting foot for articles of manufacture, having a castor mechanism incorporated therein of such construction that the furniture is automatically held

against movement when subjected to a load, while being easily and conveniently rolled from one position to another when not supporting a load. The foot is designed so that it can be cheaply and easily manufactured from sheet metal of suitable gauge by conventional cutting and bending operations without requiring special tools or dies. The metal is preferably so formed that the foot presents a smooth metallic face which can be decorated or ornamented in any desired manner by any suitable design so that the foot can be made an integral and pleasing part of the design of the furniture as a whole and harmonize therewith in color, period and the like.

The drawing illustrates the present invention as carried out in connection with different forms of furniture feet, one a curved foot 10 for use, for example, at a front corner of a studio bed, and the other a foot 11, having a flat face and adapted for use, for example, at the rear corner of a studio bed.

With reference to the foot 10 with the curved face, it comprises a body portion having a vertical face 12 which may be shaped to any desired form such as the curved form illustrated in Fig. 1 and which may receive any suitable type of decoration or ornamentation. The foot is formed of metal and is provided with an integral upper supporting flange 13 which preferably extends from one end of the foot to the other but which may be narrowed somewhat intermediate its ends, as shown at 14 in Fig. 1.

The rear foot 11 has a plane flat wall 15 formed with an upper securing flange 16 for connection to the frame of the associated article of furniture and a rear flange 17 for a similar purpose. The outer face of the wall 15 presents a surface which can be ornamented or colored for design purposes.

Each foot has incorporated as a part thereof a yieldable castor mechanism comprising a castor or roller 18 supported in a clevis 19 which is vertically movable in a guiding hasp or housing 20 welded to the inner face of the foot. The castor clevis is pressed downwardly by a helical spring 21 located between the top of the clevis and the flange 13, and surrounding a stud 22 riveted to the flange 13 and extending through an opening 23 to the interior of the clevis above the castor 18 where a head 24 is adapted to engage the periphery of the castor 18 when the furniture is subjected to a load, so as to prevent movement of the furniture.

Each end of the foot 10 and the inner end of the foot 11 is formed on the line of a symmetrical

ogee curve to facilitate manufacture and simplify the shearing operation.

The springs 21 on the various castor mechanisms are of such strength as to raise the associated article of furniture for support thereon and to lift the stud heads 23 out of engagement with the castors 18 when no one is sitting on the furniture, see Figs. 2, 4 and 5. Under such conditions the furniture is easily movable at a mere touch by rolling on the castors. However, when the furniture is subjected to body weight the springs 21 are compressed and the stud heads 24 move downwardly into engagement with the castor surfaces acting as brakes and preventing any movement of the furniture. With the parts in this position a rigid unyielding support is provided by the castor and stud.

It will be apparent that the present invention can be variously modified and adapted within the scope of the appended claims.

I claim:

1. An article of manufacture comprising in combination a foot for articles of furniture including a bracket member, a castor mechanism mounted on said bracket member and including a brake for preventing rolling of said castor mechanism, and spring means for supporting said bracket member on said castor with said brake out of engagement therewith to permit rolling on said castor, said means being adapted to yield

under load to permit said brake to engage said castor and prevent rolling thereof.

2. An article of manufacture comprising in combination a foot for articles of furniture including a bracket member, a castor mechanism mounted on the inner face of said bracket member including a castor-holding vertically movable clevis, means for guiding the vertical movement of said clevis, a brake for said castor, and a spring for supporting said bracket member on said clevis with said brake in inoperative position to permit rolling on said castor, said spring being adapted to yield under load to permit said brake to engage said castor and prevent rolling thereof.

3. A foot for articles of manufacture comprising a body portion having a reinforcing and securing flange formed along the upper edge thereof, a castor mechanism mounted on said body portion below said flange and including a vertically movable castor, a stud extending downwardly from said flange with its lower end in operative association with said castor, and yieldable means for supporting said body portion on said castor with said stud out of engagement therewith so as to permit rolling on said castor, said means being adapted to yield under body weight to permit said stud to engage said castor and prevent rolling thereof.
